UNITED STATES PATENT OFFICE.

CHARLES AUSTEN LEWIS, OF TORONTO, ONTARIO, CANADA.

PICKLE-FORK HOLDER.

Specification of Letters Patent.

Patented Jan. 6, 1920.

1,327,439.

Application filed December 16, 1918. Serial No. 266,975.

To all whom it may concern:

Be it known that I, CHARLES AUSTEN LEWIS, a subject of the King of Great Britain, and resident of the city of Toronto, 5 county of York, Province of Ontario, in the Dominion of Canada, have invented certain new and useful Improvements in Pickle-Fork Holders, as described in the following specification and illustrated in the accompanying drawings; that form part of the 10 same.

The principal object of the invention is to avoid the soiling of table linen and to devise a simple form of holder which may be 15 readily attached to the bottle and will be securely held in place and will securely hold the fork in position upon the bottle.

The principal feature of the invention consists in the novel formation of the bottle 20 and the holder, whereby engaging surfaces are formed in the bottle to secure the holder in place.

In the drawings, Figure 1 is a perspective view of a pickle bottle showing the holder 25 attached thereto, the fork being shown in dotted lines arranged in the holder.

Fig. 2 is a perspective view from the inward side of a modified form of the holder.

Fig. 3 is a transverse sectional view 30 through the form of holder shown in Fig. 35 1, taken through the line *a—b*.

Fig. 4 is a transverse sectional view through the form of holder shown in Fig. 2 illustrating the manner of gripping the 40 bottle.

Fig. 5 is an elevational view showing a further modification of holder and modified form of bottle.

The form of holder illustrated in Figs. 1 45 and 3 comprises a device formed of thin sheet metal having the back 1 of substantially elongated rectangular form, provided with a longitudinal perforation 2, the upper portion of which is provided with inwardly projecting curled edges 3.

The lower portion of the perforation 2 is adapted to receive a flanged rib projection 4 which is molded upon the outer face of the bottle 5 and the narrow neck portion 6 50 of the rib is adapted to fit in close contact with the inwardly curled edges 3 of the plate when it is slipped into position with the top of the perforation 2 resting upon the upper end of the rib projection, the 55 curled edges engaging said rib in a snug fitting spring contact.

The lower end of the back 1 is formed with a tapering pocket 7 to receive the prongs of the fork and to catch the drip from the fork and to hold the prongs in a 60 definite position in relation to the bottle.

A pair of spring arms 8 are formed upon the upper end of the back 1 and are adapted to securely grip the handle of the fork.

A holder such as described fits snugly to 65 the bottle and is held securely thereon in contact with the holding surfaces of the rib projections of the bottle. In order to provide for the attachment of the holder to a bottle which is not provided with the holding lug the longitudinal edges of the back 1 70 are curled forwardly forming the lips 9 into which the looped end of a rubber band may be inserted and passed around the bottle.

A modified form in the engaging surfaces 75 of the bottle is illustrated in Fig. 5 in that the glass is formed with a longitudinal groove 10 provided with flanged edges 11 adapted to engage the curled lips 9 of the holder, and as the metal is of spring material the lips engage the side surfaces of the groove 10 with a spring pressure which holds the device in place.

The lower portion of the groove 10 is sufficiently wide to receive the pocket 7 and 85 the flanges 11 extend upwardly from above said pocket.

In the modified form illustrated in Figs. 2 and 4 the sheet metal instead of having the longitudinal perforation 2 is stamped 90 to form a longitudinal groove 12 extending from end to end thereof. The side walls 13 of the groove 12 are perforated adjacent to the top and a pair of longitudinal flanges 14 project angularly inward from said perforations to engage the underside of the flange of the ribbed projection 4 on the bottle, as illustrated particularly in Fig. 4. The holder illustrated in Fig. 2 is otherwise of similar formation to that illustrated in 100 Fig. 1.

It will be understood that the bottles are specially formed with the projecting rib 4 or with the longitudinal groove 10 and in the preferred form, namely, that having 105 the projecting rib the holder is placed upon a bottle by inserting the rib into the lower portion of the longitudinal perforation 2 or of the groove 12. The holder is then pressed longitudinally downward to bring either 110 curled edges 3 or the longitudinal flanges 14 into engagement with the projecting rib

and when thus placed the holder is firmly secured in position.

In the form illustrated in Fig. 5 the holder is inserted into the groove 10 so that 5 the flanged lips 9 engage the flanged edges 11 of the groove and it is pushed up into the position illustrated, the upper end of the member will of course require to be slightly offset in the latter form of the invention, or the groove may be made long enough to receive the entire holder without alteration.

What I claim as my invention is:—

1. In a pickle fork holder, the combination with a bottle having grooves formed therein, of a fork holding member having projections adapted to be secured within said grooves, said fork-holding member having a pocket at its lower end.
2. In a pickle fork holder, the combination with a pickle bottle having a flanged projection, of a sheet metal holder having a pocket at its lower end to receive the fork

and longitudinally arranged contact members adapted to engage the flanged projection of the bottle. 25

3. In a pickle fork holder, the combination with a pickle bottle having a flanged projection, of a holder formed of sheet metal having a cup-shaped receptacle at one 30 end and an orifice in the back and inwardly projecting ribs adapted to extend beneath the head of the flanged projection of the bottle, said back having spring clips arranged at the upper end to hold the handle of the 35 fork.

4. In a pickle fork holder, the combination with a bottle having a projecting member, of a holder formed of a single piece of sheet metal having a cup-shaped receptacle 40 at the bottom end, longitudinally inwardly curled lips at the sides, a pair of spring holding fingers at the top and a longitudinal recess in the back adapted to receive the projecting member from the bottle.

CHARLES AUSTEN LEWIS.
